SAD-IRON SUPPORT.

1,139,688.

Specification of Letters Patent.

Patented May 18, 1915.

Application filed February 17, 1914. Serial No. 819,189.

To all whom it may concern:

Be it known that I, JOSEPH F. LAMB, a citizen of the United States, and a resident of New Britain, in the county of Hartford, 5 State of Connecticut, have invented certain new and useful Improvements in Sad-Iron Supports, of which the following is a specification.

The object of the invention is to produce 10 a simple, inexpensive and efficient stand of the kind known as the tip-up stand for use with sad irons, and particularly with electrical irons, the object being to provide a means for standing the iron on end while it 15 is not in use, so that the heated sole will not burn or otherwise damage whatever the iron happens to be placed on.

Referring to the drawings—Figure 1 is a side elevation of an iron equipped with a 20 stand made in accordance with my invention. Fig. 2 is an end view thereof, showing a modification. Fig. 3 is a perspective view of one of the supports. Fig. 4 is a perspective view of the modification.

25 Referring to the drawings, *a* denotes the sole of the iron, *b* the cover, *d* the handle, and *c* a protective socket for the terminals *f*, *f*, which as shown may be conveniently attached to the handle *d*. Near each corner 30 of the iron at the end is secured a support 10, which may be conveniently formed by bending up a strip of soft metal to U shape, reducing the ends to form shoulders 11 and projections 12 which enter apertures, as for 35 instance in the cover *b*, and are riveted or bent over to secure the support in place.

A third support 13 arranged in a plane 40 above the two corner supports 10, 10, and approximately midway between them, may conveniently form a part of the protective 45 socket *c*, and as shown in Figs. 1 to 3 inclusive, is a U-shaped member exactly like the supports 10, 10, and secured to the wall of the socket in the same way as the supports 10, 10 are secured to the iron. As shown in Fig. 4 the socket is split at its rear wall, and the ends bent outwardly to form supporting members 15, 15. That supporting member which is in the upper plane 50 and midway between the corner supports 10, 10, is slightly shorter than these corner

supports, in order that the weight of the iron shall be thrown a little beyond the vertical.

In accordance with my invention, an extremely simple stand is provided, very cheap to manufacture and assemble with the iron, and which provides an entirely satisfactory support for the iron. This stand is always in place, ready for use, is not cumbersome, and preferably the two lower supports are secured to a part of the iron which is to some extent heat-insulated from the sole, as is the case with the cover in the embodiment illustrated, it being lined with asbestos, indicated at 16. This, together with the open shape of the supports which allows of free circulation of air and the rapid radiation of the heat, removes any danger of the supports becoming so hot as to injure a table or other bearing surface.

I am aware that the device as here disclosed is susceptible of change and modification without departing from the spirit of the invention, as set forth in the appended claims.

I claim as my invention:

1. The combination with an electrical sad iron including a cover and a handle, of a support therefor comprising a pair of spaced supporting members secured to the end of said cover, a protective socket secured to said handle with its ends outwardly and projecting rearwardly of the iron to constitute a third supporting member which is above the first mentioned supporting members and located at a position approximately midway between them.

2. The combination with a sad iron including the main body of the iron, a heat-insulated cover therefor and a handle, of supports spaced from one another and secured at the end of said cover, said supports each comprising a strip of metal bent to U shape, the ends thereof being riveted in apertures in the cover, and a third support arranged above and approximately midway between the first mentioned supports.

JOSEPH F. LAMB.
